UNITED STATES PATENT OFFICE.

WILLIAM H. H. MOUNT, JR., OF MILLINGTON, NEW JERSEY.

OFFICE-PARTITION STRUCTURE.

1,267,891.

Specification of Letters Patent. Patented May 28, 1918.

Application filed April 11, 1916. Serial No. 90,355.

To all whom it may concern:

Be it known that I, WILLIAM H. H. MOUNT, Jr., a citizen of the United States, and a resident of Millington, in the county of Somerset and State of New Jersey, have invented certain new and useful Improvements in Office-Partition Structure, of which the following is a specification.

The invention relates to partitions such as are used in offices and business buildings to subdivide the space therein for the needs and requirements of a particular business. Objects and advantages of the invention will be set forth in part hereinafter, and in part will be obvious herefrom, such objects and advantages being attained through the means and instrumentalities pointed out in the accompanying claims.

The invention consists in the novel parts, constructions, arrangements, combinations and improvements herein shown and described.

The accompanying drawings, referred to herein and forming a part hereof, illustrate one embodiment of the invention, the same serving in connection with the description to explain the principles of the invention.

Of the drawings:

Figure 1 is an elevation of a partition embodying the invention;

Fig. 2 is a vertical section, on an enlarged scale, on line A—B of Fig. 1;

Fig. 3 is a horizontal section, on an enlarged scale, on line C—D of Fig. 1;

Fig. 4 is a vertical section on line E—F of Fig. 1;

Fig. 5 is a horizontal section on an enlarged scale, on line G—H of Fig. 1; and

Fig. 6 is a fragmentary horizontal section showing the junction of two partitions.

In partitions designed for erection within the permanent partition walls of buildings, which partitions are designed to subdivide space for privacy, economy and convenience in the transaction of business, it is essential or desirable to combine or realize attractive appearance, compactness, strength and rigidity of construction, with simplicity of construction, rapidity and economy of manufacture, and of fitting and erection.

In the embodiment of the invention, illustrated herewith by way of example, there is shown in Fig. 1 a partition such as might be

used to subdivide an office room, the partition being provided with a door, various features of construction being shown very much enlarged in the various sectional figures, 2 to 6.

In describing the illustrated embodiment, it will be convenient to begin at the floor, and describe the structure upwardly. A floor strip 1 is laid along the floor and secured thereto in a suitable manner, as by screw or nails. The floor strip is continuous past the different sections or panels. Such partitions are usually built with a great proportion of glass, the glass usually forming the greater part of all of the panels. In the illustrated embodiment each of the panels carries a pane of glass 2.

In Fig. 1 of the drawings a partition structure is shown with a door at the center with two panels of partition on either side of the door and extending to approximately the height of the door, with a separate series of paneling extending all the way across above the door and above the paneling on either side of the door. The various panels have a bottom rail 3 extending horizontally, a middle rail 4 and a top rail 5, likewise extending horizontally. The various panels are provided at the side with stiles 6, the panes of glass 2 being held between the rails and stiles in the usual manner, and may be secured in position by a molding 9 running thereabout. The stiles 6 at their bottoms extend below the rail 3 (see Fig. 2) and the lower ends thereof are secured to the floor rail or strip 1 in a suitable manner, as by nailing. A base 7 is provided at either side of the floor strip and extending up onto the lower rail 3 to give the proper finish.

Beginning at one side of the room, the paneling of the partition has a finishing stile 10 fitting against the wall 11 (see Fig. 5), the stile 6 of the first adjacent section fitting into and interlocking therewith, by a joint provided by the present invention. The abutting sections have their stiles 6 joining with one another and interlocking by a similar joint (see Fig. 3 at the left).

In the joint just referred to, beginning at one of the outer flat vertical surfaces of the adjoining and interlocking stiles, referring to Fig. 3, by way of example, one of the stiles has a surface 13 extending inwardly at

an angle or bevel from the exterior face 14 of the stile, said beveled surface 13 terminating preferably in a groove 15 extending in the same direction with the beveled surface 13. From the groove 15 the surface of the stiles extends forward (to the right in Fig. 3) in a direction substantially parallel to the outer surface 14 of the stile. The surface 16 terminates in a tongue 17, the surface of the stile extending from the tongue 17 out toward the other outer surface 18 of the stile by a beveled or angled surface 19, inclined in the same direction as the surface 13, and preferably parallel therewith. The adjoining stile 6 of the next panel is similarly shaped, but in reverse, whereby the two stiles may be joined together by a horizontal movement along the length of the paneling, the tongue 17 on each stile fitting into the groove 15 on the other stile, the beveled surfaces 13 and 19 interlocking and the intervening surfaces 16 contacting with each other. Thus, the stiles are locked securely against horizontal, transverse displacement.

For the purpose of providing a neat and attractive finish, a vertically extending beading 20 is formed along the outer edge of each of the surfaces 13 at its juncture with the corresponding outer surface 14 or 18 of the stile 6. A beading 21 parallel to the beading 20 is formed in each of the surfaces 14 and 18 of the stile 6 parallel to the beading 20 on the same side of the stile, and preferably opposite the beading 20 which is on the opposite surface of the stile.

This construction is of the greatest simplicity, is of great strength, and locks absolutely against transverse displacement, the entire joint construction being within the limits of the stile itself, and permitting the base to fit against the surfaces of the stile without any blocking or building out and permitting the base to be continued in one piece past each joint in the stile. The joint is also dust and light proof. This construction also does away entirely with the use of pilasters as a finish on both sides of the stiles at their juncture. It will be seen also that it furnishes an exceedingly neat, simple and strong wall joint, between the filling stile 10 which abuts with its flat back edge against the wall, and interlocks with the adjacent panel stile 6, as already described, and as shown in Fig. 5.

The joint of my invention is also applicable to the juncture of partitions joining perpendicularly to each other, as shown in Fig. 6. In such case, a finishing stile 10 is fitted with its flat back edge against the surface 14 of the stile 6, for controlling of the interlocking stiles 6, and is secured thereto in a suitable manner, as by screws 24 passing through stile 6 and into stile 10 at the back. The stile 6 of the cross partition may then

fit and interlock with the finishing stile 10. 65 This construction is simple, strong and neat, and does away with all finishing and angle strips at the juncture of the two partitions.

The top of the various panels may be finished with a crown molding 25, which may 70 be intermediate of the total height of the partition as shown in Figs. 1 and 4. Said molding comprises a dust cap 26, which as shown is a flat, horizontally extending piece fitting between the external finishing moldings 27 and 28. The moldings 27 and 28 may come down upon and inclose the upper portion of the top rail 5. The dust cap is preferably grooved or rabbeted as shown at 29 to receive the upper part of the rail 5, 80 and may be secured thereto by nails or screws 30. The dust cap and the moldings 27 and 28 are beveled to fit and lie snugly one against the other, the lower part of the molding being at an angle to fit and lie 85 snugly against the surfaces of the rail 5, the molding being fastened to the rail by nails or screws. There is thus provided an exceedingly simple and strong dust proof 90 joint, which is likewise of simple construction and which has the requisite neat and attractive appearance for a structure of this kind.

Where an upper section of partition is used, as shown in Figs. 1 and 2, it may be 95 adjustable as to size or height, the general structure being substantially the same as that already described. In such case, the bottom rail 3 thereof is manufactured loose, and the stiles 6 are cut off at a proper length 100 to make an exact fit of the upper crown molding 25 against the ceiling with the bottom of the stiles and the bottom rail resting on the dust cap of the lower part of the partition. There is thus provided, as already described, a broad and snug bearing 105 against the ceiling, providing a very firm and stable structure, and a light and dust proof joint.

Referring now to the door construction, 110 a very strong and simple structure is shown which is likewise of attractive appearance, the entire construction both in strength, simplicity and attractiveness of appearance being in keeping with the other parts of the 115 partition. At the sides of the door there is fitted into the adjoining stiles 6 a filling stile 10 (see Fig. 3) the square back of the stile forming the jamb for the door. A door stop 33 is then fastened to the filling stile, the 120 door 34 closing thereagainst. On the opposite side of the door, a similar filling stile 10 will be used, to which the door will be hung by hinges. Above the door is a door head 35, fitting into the lower crown molding and secured thereto and to the dust cap in a manner similar to the top rail 5 of the various panels, as already described. A

horizontal door stop 33 is attached to the door head 35 against which the door closes. A door stop or finishing strip 36 may be provided upon the other side of the partition, 5 especially if the door is somewhat thicker than the panel stile.

There is provided by the invention a construction and a joining of parts which is simple, strong and stable, while of neat and 10 attractive appearance. A large number of parts have been eliminated with a consequent economy in preparing the material and in construction, and a great gain in economy and in time of erection.

15 It will be understood that departures may be made from the exact structure shown and described, within the scope of the accompanying claims, without departing from the principles of the invention and without sacrificing its chief advantages.

20 What I claim as my invention and desire to secure by Letters Patent is:—

1. An office partition structure including in combination a series of vertical panels 25 connecting directly by their stiles, the contacting junctures of the stiles comprising a joint having a vertically extending surface forming an acute angle with the exterior face of the stile, said surface terminating 30 in a vertical groove, a vertically extending surface extending away from said groove substantially parallel to the outer surfaces of the stile and terminating at a vertical tongue, and a vertically extending surface 35 extending from the tongue to the other outer face of the stile substantially parallel to the first-mentioned surface, the adjoining stile having the same shape but in reverse order so that they fit together by edgewise 40 movement and lock against transverse displacement.

2. A stile for use in office partitions having a substantially flat back, sides perpendicular thereto, and its front comprising a 45 vertically extending surface starting at an acute angle from one side of the stile and terminating in a vertically extending groove, a surface extending outwardly from said groove substantially parallel to the sides of 50 the stile and terminating in a vertically extending tongue, and a vertically extending surface extending from the tongue, substantially parallel to said first-mentioned surface, to the other outer side of the guide.

55 3. An office partition structure including in combination a series of vertical panels, connecting directly by their stiles, the contacting edges of the stiles comprising a joint having a vertically extending surface forming an acute angle with the exterior face of 60 the stile, a vertically extending surface extending away from said acute angle surface and substantially parallel to the outer surfaces of the stile, and a vertically extending

surface extending from said last-mentioned 65 vertically extending surface to the other outer face of the stile in the same direction as the first-mentioned acute angle vertically extending surface, the adjoining stile having the same shape but in reverse position, so that they fit together by edgewise 70 movement and lock against transverse displacement.

4. An office partition intersecting structure including in combination a series of 75 vertical panels in alinement and having stiles abutting together by a joint comprising a vertically extending surface starting at an oblique angle at the side of the stiles and terminating within the stiles, a vertically 80 extending surface extending therefrom in a direction substantially parallel to the outer sides of the stiles, and a vertically extending surface extending out to the opposite side of the stiles at an angle in the same 85 direction as the first-mentioned vertically extending surface, and a partition abutting upon said first-mentioned partition and having a filling stile with a flat back, said back abutting against a stile in the first-mentioned 90 partition and fastened thereto, the abutting partition comprising panels, one of said panels adjoining said filling stile and directly interlocking therewith by a similar joint to that described above. 95

5. In a panel partition, the combination of a series of panel frames having stiles with outer edges in direct engagement to form a continuous panel framework of uniform thickness throughout, each of the mutually 100 engaging stiles having its adjoining edge formed with two longitudinally extending transverse surfaces and an intermediate, longitudinally extending surface approximately in a plane midway between and parallel to 105 the side surfaces of the stile, the said transverse surfaces forming acute angles with the other said surface, whereby the panel frames are interlocked by edgewise movement.

6. A stile for paneled partitions having a 110 joining edge adapted to interlock directly with the similar edge of another stile, being formed with longitudinally extending transverse surfaces which terminate at the opposite sides of the stile in longitudinally extending transverse planes spaced from each other, and the stile being formed with a longitudinally extending bead on a side surface adjacent one of said transverse surfaces and with a second longitudinal bead on a 115 side surface and spaced from a transverse edge surface of the stile a distance proportional to the distance between the said transverse planes.

7. A stile for paneled partitions having a 120 joining edge adapted to interlock directly with the similar edge of another stile, being formed with two longitudinally extending

transverse surfaces and an intermediate, longitudinally extending surface approximately in a plane midway between and parallel to the side surfaces of the stile, the said transverse surfaces forming acute angles with the other said surface, and the stile being formed with a longitudinally extending bead on a side surface adjacent one of said transverse edge surfaces and with a second longitudinal bead on a side surface and spaced from

a transverse edge surface of the stile a distance proportional to the width of the said intermediate surface.

In testimony whereof, I have signed my name to this specification, in the presence of 15 two subscribing witnesses.
